(57) **CLAIM**

We claim, the ornamental design for a measurement device, as shown and described.

DESCRIPTION

FIG. 1 is a front plan view of a third embodiment the invention;

FIG. 2 is a rear plan view of the embodiment of FIG. 1;
FIG. 3 is a first side plan view of the embodiment of FIG. 1;
FIG. 4 is a second side plan view of the embodiment of FIG. 1;

FIG. 5 is a bottom plan view of the embodiment of FIG. 1;
FIG. 6 is a top plan view of the embodiment of FIG. 1;
FIG. 7 is a first perspective view of the embodiment of FIG. 1;
FIG. 8 is a second perspective view of the embodiment of FIG. 1; and,

FIG. 9 is a third perspective view of the embodiment of FIG. 1.

The phantom lines shown in FIG. 1-FIG. 9 are environmental and not part of the claimed design.

The color and shading shown in FIG. 1-FIG. 9 forms no part of the claimed design, the measurement device according to the claimed design may be any color or combination of colors.

The surface treatment shown in FIG. 1-FIG. 9 forms no part of the claimed design, the measurement device of the claimed design may have any surface treatment.

References to “side”, “top”, “front”, “rear” and “bottom” in the figure descriptions are not meant to require certain in-use orientation; a measurement device according to the claimed design may be used in any orientation.
